CLAIM

The ornamental design for a combined protective cake cover and candle holder, substantially as shown and described.

DESCRIPTION

FIG. 1 is a top plan view of a combined protective cake cover and candle holder showing my new design;
FIG. 2 is a side elevation thereof;
FIG. 3 is a bottom plan view thereof; and
FIG. 4 is an enlarged cross-section taken along the line 4—4 of FIG. 1.

FIG. 1

FIG. 2

FIG. 4
